OTHER PUBLICATIONS

Design U.S. Appl. No. 29/483,556, filed Feb. 28, 2014, entitled "Grip for Hand Tool," Inventor: Michael H. Reedy.

Primary Examiner — Ian Simmons

Assistant Examiner — Harold Blackwell, II

(57) **CLAIM**

The ornamental design for a "grip for hand tool," as shown and described.

DESCRIPTION

FIG. 1 is a perspective view of the grip for a hand tool;
 FIG. 2 is a front view of the grip for a hand tool;
 FIG. 3 is a rear view of the grip for a hand tool;
 FIG. 4 is a right side view of the grip for a hand tool;
 FIG. 5 is a left side view of the grip for a hand tool;
 FIG. 6 is a bottom view of the grip for a hand tool;
 FIG. 7 is a top view of the grip for a hand tool; and,
 FIG. 8 is a perspective view of the grip for a hand tool.
 The head of the hand tool shown in broken lines illustrates the unclaimed environment of the claimed design. The remaining broken lines in the drawings illustrate portions of the grip for hand tool which form no part of the claimed design.
